(57) **ABSTRACT**

Provided are a heating element, which includes: a transparent substance; a conductive heating line that is provided on at least one side of the transparent substance; bus bars that is electrically connected to the conductive heating line; and a power portion that is connected to the bus bars, wherein 30% or more of the entire area of the transparent substance has a conductive heating line pattern in which, when the

(Continued)

straight line that intersects the conductive heating line is drawn, a ratio (distance distribution ratio) of standard deviation in respects to an average value of distances between adjacent intersection points of the straight line and the conductive heating line is 5% or more, and a method for manufacturing the same.

HEATING ELEMENT AND
MANUFACTURING METHOD THEREOF

This application is a Continuation-in-part of U.S. application Ser. No. 12/934,607, filed on Sep. 24, 2010, and U.S. patent application Ser. No. 12/934,605, filed on Sep. 24, 2010, and claims the benefit of Korean Application No. 10-2008-0055807, filed on Jun. 13, 2008, Korean Application No. 10-2008-0119121, filed Nov. 27, 2008, and Korean Application No. 10-2008-0119122, filed Nov. 27, 2008 all of which are hereby incorporated by reference in their entirety for all purposes as if fully set forth herein.

The present application is a continuation-in-part application of U.S. patent application Ser. Nos. 12/934,607 and 12/934,605.

TECHNICAL FIELD

The present invention relates to a heating element and a method for manufacturing the same. More particularly, the present invention relates to a heating element that includes a pattern that is not well visible, has excellent heating performance at a low voltage, and is capable of minimizing diffraction and interference of light, and a method for manufacturing the same.

BACKGROUND ART

In winter or rainy day, frost is formed on a glass surface of a vehicle because of a difference between temperatures of the outside and inside of the vehicle. In addition, in the case of an indoor ski resort, a freezing phenomenon occurs because of a difference between temperatures of the inside where there is a slope and the outside of the slope. In order to solve this, a heating glass has been developed. The heating glass uses a concept where after a hot line sheet is attached to the glass surface or a hot line is directly formed on the glass surface, a current is applied to both terminals of the hot line to generate heat from the hot line, thereby increasing the temperature of the glass surface. It is important that the heating glass for vehicle or construction has low resistance in order to smoothly generate heat, but it should not be offensive to human eye. Accordingly, methods for manufacturing a known transparent heating glass by forming a heating layer through a sputtering process using a transparent conductive material such as ITO (Indium Tin Oxide) or Ag thin film and connecting an electrode to a front end thereof have been proposed. However, the heating glass according to the above method has a problem in that it is difficult to drive it at a low voltage of 40 V or less because of high surface resistance.

DISCLOSURE

Technical Problem

In order to solve the above problems, the present invention has been made in an effort to provide a heating element that is not well visible, can minimize side effects by diffraction and interference of single light source after sunset and has excellent heating performance at a low voltage, and a method for manufacturing the same.

Technical Solution

In order to accomplish the above object, an exemplary embodiment of the present invention provides a heating

2

element comprising a transparent substance; a conductive heating line that is provided on at least one side of the transparent substance; bus bars that is electrically connected to the conductive heating line; and a power portion that is connected to the bus bars, wherein 30% or more of the entire area of the transparent substance has a conductive heating line pattern in which, when a straight line that intersects the conductive heating line is drawn, a ratio (distance distribution ratio) of standard deviation in respects to an average value of distances between adjacent intersection points of the straight line and the conductive heating line is 5% or more. The straight line that intersects the conductive heating line means a line where the distance deviation of the most closely adjacent intersection points of the pattern that is generated by the line is small. In addition, it may be a line that vertically extends in respects to the tangent line of any one point.

Another exemplary embodiment of the present invention provides a heating element, which includes: a transparent substance; a conductive heating line that is provided on at least one side of the transparent substance; bus bars that is electrically connected to the conductive heating line; and a power portion that is connected to the bus bars, wherein the standard deviation value of the intensity of light for each 5° in a circumferential direction of the light source which is measured when the light emitted from the light source that is disposed at the distance of 7 m from the heating element passes through the heating element is 15 or less.

Still another exemplary embodiment of the present invention provides a method for manufacturing a heating element, which includes: forming a conductive heating line on a transparent substance; forming bus bars that is electrically connected to the conductive heating line; and forming a power portion that is connected to the bus bars, wherein, on 30% or more of the entire area of the transparent substance, the heating element is formed in a pattern in which, when a straight line that intersects the conductive heating line is drawn, a ratio (distance distribution ratio) of standard deviation in respects to an average value of distances between adjacent intersection points of the straight line and the conductive heating line is 2% or more. The conductive heating line may be formed by using a printing method, a photolithography method, a photography method, a method using a mask, a sputtering method, or an inkjet method.

An exemplary embodiment of the present invention provides a heating element comprising a transparent substance; a conductive heating line that is provided on at least one side of the transparent substance; bus bars that is electrically connected to the conductive heating line; and a power portion that is connected to the bus bars, wherein 30% or more of the entire area of the transparent substance has a conductive heating line pattern in which is formed of closed figures where a distribution is continuous and a ratio (area distribution ratio) of a standard deviation in respects to an average value of areas of the closed figures is 5% or more.

Another exemplary embodiment of the present invention provides a method for manufacturing a heating element, which includes: forming a conductive heating line on a transparent substance; forming bus bars that is electrically connected to the conductive heating line; and forming a power portion that is connected to the bus bars, wherein, on 30% or more of the entire area of the transparent substance, the conductive heating line is formed in a pattern that is formed of closed figures in which distributions are continuous and a ratio (distance distribution ratio) of standard deviation in respects to an average value of areas of the closed figures is 5% or more. The conductive heating line

may be formed by using a printing method, a photolithography method, a photography method, a method using a mask, a sputtering method, or an inkjet method.

Advantageous Effects

According to the exemplary embodiments of the present invention, the heating element can minimize side effects by diffraction and interference of single light source after sunset, has excellent heating performance at a low voltage and is not well visible. In addition, since the heating element according to an exemplary embodiment of the present invention can be formed by using various methods such as using a printing method, a photolithography method, a photography method, a method using a mask, a sputtering method, or an inkjet method after a desired pattern is previously set, the process is easily performed and the cost is low.

DESCRIPTION OF DRAWINGS

BEST MODE

Hereinafter, the present invention will be described in detail.

A heating element according to an exemplary embodiment of the present invention includes a transparent substance; a conductive heating line that is provided on at least one side of the transparent substance; bus bars that are electrically connected to the conductive heating line; and a power portion that is connected to the bus bars, wherein 30% or more of the entire area of the transparent substance has a conductive heating line pattern in which, when a straight line that intersects the conductive heating line is drawn, a ratio (distance distribution ratio) of standard deviation in respects to an average value of distances between adjacent intersection points of the straight line and the conductive heating line is 5% or more.

A heating element according to an exemplary embodiment of the present invention includes a transparent substance; a conductive heating line that is provided on at least one side of the transparent substance; bus bars that are electrically connected to the conductive heating line; and a power portion that is connected to the bus bars, wherein 30% or more of the entire area of the transparent substance has a conductive heating line pattern in which is formed of closed

figures where a distribution is continuous and a ratio (area distribution ratio) of a standard deviation in respects to an average value of areas of the closed figures is 5% or more.

As shown in the related art, in the case of when the transparent front side heating layer is formed, there is a problem in that resistance is very high. In addition, in the case of when the heating line is formed in a regular pattern having one or more shapes such as a grid manner or linear manner, diffraction and interference patterns of light may be generated by a difference between refractive indexes of the heating line and transparent substance. The patterns maximize the effect by the light source that is present after sunset such as headlight of the vehicle or streetlamp. Therefore, in the case of when the heating element that has the heating line is applied to the front window of the vehicle, the diffraction and interference patterns of light as described above may make safety and the degree of fatigue of the driver serious.

In the present invention, as described above, it is possible to prevent side effects by the interference of the light source that can be detected by the naked eye in a dark area because 30% or more, preferably 70%, and more preferably 90% or more of the entire area of the transparent substance has the pattern where, when the straight line that intersects the conductive heating line is drawn, the ratio (distance distribution ratio) of the standard deviation in respects to the average value of distances of the adjacent intersection points of the straight line and the conductive heating line is 5% or more.

In the present invention, it is preferable that the straight line that intersects the conductive heating line is a line in which the standard deviation of the distances between adjacent intersection points of the straight line that intersects the conductive heating line and the conductive heating line is the smallest value. In addition, it is preferable that the straight line that intersects the conductive heating line is a straight line that vertically extends in respects to the tangent line of any one point of the conductive heating lines.

In the heating element according to an exemplary embodiment of the present invention, it is preferable that the straight line that intersects the conductive heating line has 80 or more intersection points with the conductive heating line.

Diffraction and interference of light by the single light source closely relate to randomness of the pattern. When a line starting from the center of the light source is drawn for each angle, an interference pattern is formed according to the number of lines vertically meeting the pattern and a distance from the center. For example, in the case where a quadrangle pattern is formed, as illustrated in the following FIG. 28, lines are formed side to side and up and down.

In this case, when the line starting from the center of the light source is drawn for each angle, if randomness is given to the number of lines vertically meeting the pattern and the distance from the center, the interference pattern spreads for each angle, and through this, the interference pattern does not emerge, and as illustrated in the following FIG. 29, the light source is scattered.

In order to satisfy the aforementioned condition, in the present invention, the degree of weakening the interference pattern is adjusted by adjusting the ratio (distance distribution ratio) of standard deviation in respects to the average value of the distances between the adjacent intersection points of the straight line that intersects the conductive heating line and the conductive heating line.

The ratio (distance distribution ratio) of standard deviation in respects to an average value of distances between adjacent intersection points of the straight line that intersects the conductive heating line and the conductive heating line

is preferably 5% or more, more preferably 10% or more, and even more preferably 20% or more.

In the present invention, there is suggested a method for digitalizing the degree of weakening the interference pattern by making the aforementioned heating line pattern irregular. It is possible to provide the heating element that has the optical property where the standard deviation value of the intensity of light for every 5° in a circumferential direction of the light source which is measured when light that is emitted from the light source that is disposed at the distance of 7 m from the heating element passes through the heating element is 15 or less. It is possible to prevent side effects by the diffraction and the interference of the light source that may be detected by the naked eye in a dark area by the aforementioned property.

Since there may be present a deviation according to the kind of light source, in the present invention, as the standard light source, an incandescent lamp of 100 W is used. The intensity of light is measured through a digital camera. The 20 photographing condition of the camera is set so that, for example, F (aperture value) is 3.5, a shutter speed is $1/100$, ISO is 400 and a black and white image is ensured. After the image is obtained by using the camera as described above, the intensity of light may be rated through an image analysis.

In the present invention, when the intensity of light is measured, the light source is disposed at the center of the black box that has the width of 30 cm, length of 15 cm, and the height of 30 cm, and the equipment where the circle that has the diameter of 12.7 mm is opened before the point of 30 7.5 cm from the center of the light source is used. The light source of the double phase measurement equipment device according to KS L 2007 standard is adopted. The digital image that is obtained by using the above condition is stored in 1600×1200 pixels, the intensity of light per each pixel is 35 represented by the numerical value in the range of 0 to 255, and the area in the light source area per each pixel has the value in the range of 0.1 to 0.16 mm².

On the basis of the intensity of light per the pixel of the digital image, on the basis of the sum total of the left, right/upper and lower intensities, the position of the central pixel of the light source is obtained. On the basis of the central pixel of the light source, the average value of the intensities of light for each 5° by dividing the sum total of intensities of light of the pixel that corresponds to the angle of 5° by the number of the pixel. In the pixel that is used I the calculation, all pixels of 1200×1600 are not used, but when it is assumed that one pixel corresponds to the distance 1 by reducing the pixel as the coordinate value, only pixels that are present within the distance of 500 or less from the central pixel of the light source are used. Since the average value is calculated as one value for each 5°, if it is reduced into 360°, 72 values are obtained. Therefore, the standard deviation that is calculated in the present invention is a value that corresponds to 72 standard deviations.

It is preferable that the measurement of the intensity of light is performed in the dark room. FIG. 8 illustrates the configuration of the equipment.

In the present invention, the standard deviation value of the intensity of light for each 5° in a circumferential direction of the light source which is measured when light that is emitted from the light source that is disposed at the distance of 7 m from the heating element passes through the heating element may be 15 or less, more preferably 10 or less, and more preferably 5 or less. If the aforementioned standard deviation value is 15 or less, the degree of spreading of light in the circumferential direction may be reinforced to minimize obstruction of a field of vision by an interference

pattern, and if the value is 10 or less, a level at which the interference pattern of light is not visually sensed may be attained.

It is preferable that the pattern in which the ratio (distance distribution ratio) of standard deviation in respects to an average value of distances between adjacent intersection points of the straight line that intersects the conductive heating line and the conductive heating line is preferably 5% or more is 30% or more in respects to the entire area of the transparent substance. As described above, the other type conductive heating line may be provided on a portion of the at least one side of the surface of the transparent substance that is provided with the heating line pattern.

In the present invention, if randomness of the pattern is excessively increased, a concentration degree of the pattern is different for each portion, and thus an increase in the degree of scattering by the pattern occurs. Accordingly, in a state where the concentration degree for each portion of the irregular pattern is controlled, randomness needs to be adjusted.

In the present invention, in order to adjust the concentration degree of the pattern, the pattern where the ratio (distance distribution ratio) of standard deviation in respects to the average value of the distances between the adjacent intersection points of the straight line that intersects the conductive heating line and the conductive heating line is 5% or more may be constituted in a form of lines linking vertexes with each other after in an area in which the pattern is to be formed, a polygon having an area of a predetermined size, such as a triangle, a rectangle, a square, a direct hexagon, and a regular hexagon is designated as a basic unit and positions of the vertexes of the polygon are randomly changed.

In order to prevent the changed position of the vertex from being the same as the position of another vertex, as illustrated in FIG. 20(A), after the unit area where the position of each vertex may be changed is determined, as illustrated in FIG. 20(B), each vertex may be moved to a predetermined point in each unit area. For example, as illustrated in FIG. 20(A), in the case where a circle is designated as the unit area, randomness may be adjusted by a ratio of a diameter of the circle that is the unit area and a length of one side of the basic unit. In the present invention, the randomness may be defined as a value obtained by dividing the diameter of the circle that is the unit area by the length of the side of the basic unit. In this case, in the case where the basic unit is a polygon of a regular hexagon and the randomness value is 0%, a structure of a regular honeycomb form may be attained, and as the randomness is increased, the randomness of the pattern may be increased. If the irregular pattern is formed by applying the aforementioned manner, in a state where the concentration degree of the pattern is controlled, the randomness of the pattern may be controlled. In the unit area, each vertex may be randomly selected to be disposed. In this case, a ratio of moving each vertex to a predetermined point in each unit area may be 10% or more, 20% or more, and 30% or more, but is not limited thereto. The unit area may have a form such as circle and quadrangle with each vertex as a center point of mass.

As another example, lines of the polygon may be modified in various forms. For example, the aforementioned lines may be simply a straight line, a curved line, a zigzag line, or a combination thereof. For example, modification in various forms, such as modification of curvatures of the lines of the figures of FIGS. 20(A) or 20(B), may be performed.

An example of a manner of manufacturing the curved line is as follows. For example, the line may be modified in a

circumference form of a circle passing through two adjacent vertexes of the polygon. In this case, when the straight lines are drawn from the original point of the circle to the two vertexes of the polygon, the pattern may be designed as illustrated in FIG. 20(C) by selecting the circle where an angle (curvature) θ_c formed by the two straight lines is constant, and then linking the vertexes with each other along the circumference of the circle.

10 In the present invention, as described above, it is possible to prevent side effects by the interference of the light source that can be detected by the naked eye in a dark area because 30% or more, preferably 70%, and more preferably 90% or more of the entire area of the transparent substance has a conductive heating line pattern in which is formed of closed figures where a distribution is continuous and a ratio (area distribution ratio) of a standard deviation in respects to an average value of areas of the closed figures is 5% or more.

15 In the heating element according to an exemplary embodiment of the present invention, it is preferable that there are 100 closed figures.

20 Diffraction and interference of light by the single light source closely relate to randomness of the pattern. When a line starting from the center of the light source is drawn for each angle, an interference pattern is formed according to the number of lines vertically meeting the pattern and a distance from the center. For example, in the case where a quadrangle pattern is formed, as illustrated in the following FIG. 28, lines are formed side to side and up and down.

25 In this case, when the line starting from the center of the light source is drawn for each angle, if randomness is given to the number of lines vertically meeting the pattern and the distance from the center, the interference pattern spreads for each angle, and through this, the interference pattern does not emerge, and as illustrated in the following FIG. 29, the light source is scattered.

30 In order to satisfy the aforementioned condition, in the present invention, the degree of weakening the interference pattern is adjusted by adjusting the ratio (area distribution ratio) of standard deviation in respects to an average value of areas of the closed figures.

35 The ratio (distance distribution ratio) of standard deviation in respects to an average value of areas of the closed figures is preferably 5% or more, more preferably 10% or more, even more preferably 20% or more.

40 In the present invention, the standard deviation value of the intensity of light for every 5° in a circumferential direction of the light source which is measured when light that is emitted from the light source that is disposed at the distance of 7 m from the heating element passes through the heating element may be 15 or less, more preferably 10 or less, and more preferably 5 or less. If the aforementioned standard deviation value is 15 or less, the degree of spreading of light in the circumferential direction may be reinforced to minimize obstruction of a field of vision by an interference pattern, and if the value is 10 or less, a level at which the interference pattern of light is not visually sensed may be attained.

45 It is preferable that the pattern that is formed of the closed figures having the ratio (distance distribution ratio) of standard deviation in respects to an average value of areas thereof is 5% or more is preferable to 30% or more in respects to the entire area of the transparent substance. As described above, the other type conductive heating line may be provided on a portion of the at least one side of the surface of the transparent substance that is provided with the heating line pattern.

In the present invention, the pattern formed of the closed figures where the ratio (area distribution ratio) of standard deviation in respects to the average value of the areas is 5% or more may be constituted in a border form of a polygon linking vertexes after in an area in which the pattern is to be formed, a polygon having an area of a predetermined size, such as a triangle, a rectangle, a square, a direct hexagon, and a regular hexagon is designated as a basic unit and positions of the vertexes of the polygon are randomly changed.

Further, the pattern formed of the closed figures where the ratio (area distribution ratio) of standard deviation in respects to the average value of the areas is 5% or more may be constituted in a border form of a polygon modified so that changed center points of mass become new center points of mass after in an area in which the pattern is to be formed, a polygon having an area of a predetermined size, such as a triangle, a rectangle, a square, a direct hexagon, and a regular hexagon is designated as a basic unit and positions of the center points of mass of the polygons are randomly changed in the polygon.

In order to prevent the changed position of the vertex from being the same as the position of another vertex, as illustrated in FIG. 20(A), after the unit area where the position of each vertex may be changed is determined, as illustrated in FIG. 20(B), each vertex may be moved to a predetermined point in each unit area. In this case, a ratio of moving each vertex to a predetermined point in each unit area may be 10% or more, 20% or more, and 30% or more, but is not limited thereto. The unit area may be a form such as circle and quadrangle with each vertex as a center point of mass.

As another example, lines of the polygon may be modified in various forms. For example, the aforementioned lines may be simply a straight line, a curved line, a zigzag line, or a combination thereof. For example, modification in various forms, such as modification of curvatures of the lines of the figures of FIGS. 20(A) or 20(B), may be performed.

An example of a manner of manufacturing the curved line is as follows. For example, the line may be modified in a circumference form of a circle passing through two adjacent vertexes of the polygon. In this case, when the straight lines are drawn from the original point of the circle to the two vertexes of the polygon, the pattern may be designed as illustrated in FIG. 20(C) by selecting the circle where an angle θ_c formed by the two straight lines is constant, and then linking the vertexes with each other along the circumference of the circle.

As the exemplary embodiment of the present invention, a form of the pattern having a regular hexagon form as the basic unit, in which the position of the vertex of the regular hexagon is changed, is illustrated in the following FIGS. 21 to 24. More specifically, the following FIG. 21 illustrates a method of modifying the positions of the vertexes of the regular hexagon, the following FIG. 22 illustrates a form where randomness of the pattern and curvature of the line are modified, and the following FIG. 23 illustrates a form where randomness of the pattern is modified. Further, the following FIG. 24 is a view illustrating a correlation between the standard deviation value of the intensity of light for each 5° in the circumferential direction of the light source which is measured when light that is emitted from the light source that is disposed at the distance of 7 m from the heating element passes through the heating element and the ratio (area distribution ratio) of standard deviation in respects to the average value of the areas of the closed figures.

In the present invention, as described above, by making the pattern of the heating line irregular, it is possible to provide the heating element that has the optical property where the standard deviation value of the intensity of light for each 5° in a circumferential direction of the light source which is measured when the light that is emitted from the light source that is disposed at the distance of 7 m from the heating element passes through the heating element is 15 or less. By this physical property, it is possible to prevent side effects by the interference of the light source that can be detected by the naked eye in a dark area.

Since there may be present a deviation according to the kind of light source, in the present invention, as the standard light source, an incandescent lamp of 100 W is used. The 15 intensity of light is measured through a digital camera. The photographing condition of the camera is set so that, for example, F (aperture value) is 3.5, a shutter speed is $1/100$, ISO is 400 and a black and white image is ensured. After the 20 image is obtained by using the camera as described above, the intensity of light may be rated through an image analysis.

In the present invention, when the intensity of light is measured, the light source is disposed at the center of the black box that has the width of 30 cm, length of 15 cm, and the height of 30 cm, and the equipment where the circle that 25 has the diameter of 12.7 mm is opened before the point of 7.5 cm from the center of the light source is used. The light source of the double phase measurement equipment device according to KS L 2007 standard is adopted. The digital 30 image that is obtained by using the above condition is stored in 1600×1200 pixels, the intensity of light per each pixel is represented by the numerical value in the range of 0 to 255, and the area in the light source area per each pixel has the value in the range of 0.1 to 0.16 mm^2 .

On the basis of the intensity of light per the pixel of the 35 digital image, on the basis of the sum total of the left, right/upper and lower intensities, the position of the central pixel of the light source is obtained. On the basis of the central pixel of the light source, the average value of the 40 intensities of light for each 5° by dividing the sum total of intensities of light of the pixel that corresponds to the angle of 5° by the number of the pixel. In the pixel that is used I the calculation, all pixels of 1200×1600 are not used, but when it is assumed that one pixel corresponds to the distance 45 1 by reducing the pixel as the coordinate value, only pixels that are present within the distance of 500 or less from the central pixel of the light source are used. Since the average value is calculated as one value for each 5° , if it is reduced into 360° , 72 values are obtained. Therefore, the standard deviation that is calculated in the present invention is a value 50 that corresponds to 72 standard deviations.

It is preferable that the measurement of the intensity of light is performed in the dark room. FIG. 8 illustrates the configuration of the equipment.

In the present invention, when light that is emitted from 55 the light source that is distant from the heating element by 7 m penetrates the heating element, the standard deviation value of the intensities of light that is measured per each 5 in a circumferential direction of light source is 15 or less, more preferably 13 or less, and more preferably 10, and much more preferably 5 or less.

Meanwhile, in the case of when the patterns are completely irregular, in the distribution of the line, there may be a difference between a loose portion and a dense portion thereof. The distribution of the line may be visible by the eye 60 even though the line width is very thin. In order to solve this problem of sight recognition, in the present invention, when the heating line is formed, regularity and irregularity may be

appropriately harmonized. For example, the basic unit is set so that the heating line is visible or local heating is not formed, and in the basic unit, the heating line may be formed in an irregular pattern. If the above method is used, the visibility can be compensated by preventing the localization of the distribution of lines on the one point.

As described above, for the uniform heating and visibility of the heating element, it is preferable that the opening ratio of the pattern is constant in the unit area. It is preferable that the transmittance deviation of the heating element is 5% or less in respects to a predetermined circle that has the diameter of 20 cm. In this case, the heating element may prevent the local heating. In addition, in the heating element, it is preferable that after the heating, the standard deviation of the surface temperature of the transparent substance is within 20%.

In the present invention, the heating line may be formed of the straight lines, or various modifications such as curved lines, wave lines, and zigzag lines may be feasible.

FIG. 1 and FIG. 2 illustrate a state in which a predetermined line is drawn on a pattern of a conductive heating line according to an exemplary embodiment of the present invention. However, the scope of the present invention is not limited thereto. FIG. 1 illustrates an one dimension state in which the conductive heating lines do not cross each other, and FIG. 2 illustrates a two dimension state in which the conductive heating lines cross each other and a closed figure is formed on some areas. An example of the other conductive heating line pattern is illustrated in FIG. 5, but the scope of the present invention is not limited thereto.

FIG. 10 illustrates a pattern of a conductive heating line of the heating element according to an exemplary embodiment of the present invention. The area distribution ratio of the pattern is 20% or more, for example, 20 to 35%.

According to an exemplary embodiment of the present invention, the conductive heating line pattern may be a boundary shape of the figures that form a Voronoi diagram.

In the present invention, side effects by diffraction and interference of light can be minimized by forming the conductive heating line pattern in a boundary form of figures that configure the Voronoi diagram. The Voronoi diagram is a pattern that is formed by filling the closest area from the corresponding dot as compared to the distance of the dot from the other dots if Voronoi diagram generator dots are disposed in an area that will be filled. For example, when large discount stores in the whole country are represented by dots and consumers find the closest large discount store, the pattern that displays the commercial area of each discount store may be exemplified. That is, if the space is filled with regular hexagon and each dot of the regular hexagon is set by the Voronoi generator, the conductive heating line pattern may be a honeycomb structure. In the present invention, in the case of when the conductive heating line pattern is formed, there is an advantage in that the complex pattern form that can minimize the side effects by the diffraction and interference of light can be easily determined. FIG. 4 illustrates the forming of the pattern using the Voronoi diagram generator.

An example of the other conductive heating line pattern is illustrated in FIGS. 11 to 13, but the scope of the present invention is not limited thereto.

In the present invention, the pattern that is obtained from the generator may be used by regularly or irregularly positioning the Voronoi diagram generator.

In the case of when the conductive heating line pattern is formed in a boundary form of the figures that form the Voronoi diagram, as described above, in order to solve the

recognition problem, when the Voronoi diagram generator is generated, the regularity and irregularity may be appropriately harmonized. For example, after the area having a predetermined size is set as the basic unit in the area in which the pattern is provided, the dots are generated so that the distribution of dots in the basic unit has the irregularity, thus manufacturing the Voronoi pattern. If the above method is used, the visibility can be compensated by preventing the localization of the distribution of lines on the one point.

As described above, in the case of when the opening ratio of the pattern is made constant in the basic unit area for the uniform heating and visibility of the heating element, it is possible to control the number per unit area of the Voronoi diagram generator. In this case, when the number per unit area of the Voronoi diagram generator is uniformly controlled, the unit area is preferably 5 cm² or less and more preferably 1 cm² or less. The number per unit area of the Voronoi diagram generator is preferably 25 to 2,500/cm² and more preferably 100 to 2,000/cm².

Among the figures that form the pattern in the unit area, at least one has preferably the different shape from the remaining figures.

According to another exemplary embodiment of the present invention, the conductive heating line pattern may be a boundary form of the figures that are formed of at least one triangle forming the Delaunay pattern. In detail, the form of the conductive heating line pattern is a boundary form of the triangles that form the Delaunay pattern, a boundary form of the figures formed of at least two triangles that form the Delaunay pattern or a combination thereof.

The side effects by diffraction and interference of light may be minimized by forming the boundary form of the figures that are formed of at least one triangle that forms the Delaunay pattern by using the conductive heating line pattern. The Delaunay pattern is a pattern that is formed by disposing the Delaunay pattern generator dots in the area in which the pattern will be filled and drawing a triangle by connecting three dots therearound so that when the circumcircle that includes all corners of the triangle is drawn, there is no other dot in the circle. In order to form the pattern, Delaunay triangulation and circulation may be repeated on the basis of the Delaunay pattern generator. The Delaunay triangulation may be performed in such a way that a thin triangle is avoided by maximizing the minimum angle of all angles of the triangle. The concept of the Delaunay pattern was proposed by Boris Delaunay in 1934. An example of formation of the Delaunay pattern is shown in FIG. 14. In addition, an example of the Delaunay pattern is shown in FIG. 15 and FIG. 16. However, the scope of the present invention is not limited thereto.

The pattern of the boundary form of the figures that are formed of at least one triangle that forms the Delaunay pattern may use the pattern that is obtained from the generator by regularly or irregularly positioning the Delaunay pattern generator. In the present invention, in the case of when the conductive heating line pattern is formed by using the Delaunay pattern generator, there is an advantage in that the complex pattern form that can minimize the side effects by the diffraction and interference of light can be easily determined.

In the case of when the conductive heating line pattern is formed in a boundary form of the figures that are formed of at least one triangle that forms the Delaunay pattern, as described above, in order to solve the recognition problem and local conductivity problem, when the Delaunay pattern generator is generated, the regularity and irregularity may be appropriately harmonized. For example, an irregular and

uniform standard dot is generated in the area in which the pattern is provided. In this case, the irregularity means that the distances between the dots are not constant, and the uniformity means that the numbers of the dots that are included per unit area are the same as each other.

An example of the method for generating the irregular and uniform standard dots will be exemplified below. As shown in FIG. 18A, a predetermined dot is generated on the entire surface. After that, the interval between the generated dots is measured, and in the case of when the interval between the dots is smaller than the value that is previously set, the dots are removed. In addition, the Delaunay triangle pattern is formed on the basis of the dots, and in the case of when the area of the triangle is larger than the value that is previously set, the dots are added in the triangle. If the above process is performed repeatedly, as shown in FIG. 18B, the irregular and uniform standard dots are generated. Next, the Delaunay triangle that includes one generated standard dot is generated. In this step, it may be performed by using the Delaunay pattern. If the above method is used, the visibility can be compensated by preventing the localization of the distribution of lines on the one point.

As described above, in the case of when the opening ratio of the pattern is made constant in the basic unit area for the uniform conductivity and visibility of the heating element, it is possible to control the number per unit area of the Voronoi diagram generator. In this case, when the number per unit area of the Delaunay pattern generator is uniformly controlled, the unit area is preferably 5 cm² or less and more preferably 1 cm² or less. The number per unit area of the Voronoi diagram generator is preferably 25 to 2,500/cm² and more preferably 100 to 2,000/cm².

Among the figures that form the pattern in the unit area, at least one has preferably the different shape from the remaining figures.

In the present invention, the aforementioned heating line pattern may have a pattern form that is slightly different from a general Voronoi pattern or Delaunay pattern in the related art. The Voronoi pattern and the Delaunay pattern that are commonly called are terms including both a regular pattern and an irregular pattern, but in the present invention, the center point of mass is generated so that distribution of the center points of mass has randomness in the basic unit, and the heating line pattern is formed by using the center point of mass or is formed by modifying the positions of the vertexes of the polygons constituting the basic unit to have randomness, and thus only an area having only a standard deviation at a specific level may be defined as the area of the present invention.

For example, as the exemplary embodiment of the present invention, comparing to uniformities of opening ratios of the heating line pattern formed through the basic unit of the uniform square and the general irregular Voronoi pattern to each other, it can be confirmed as illustrated in the following FIGS. 25 and 26, that in the present invention, the opening ratio is uniform, but the opening ratio of the general irregular Voronoi pattern is not uniform.

In the present invention, when the straight line that intersects the conductive heating line is drawn, the conductive heating line pattern may simultaneously satisfy characteristics where the ratio (distance distribution ratio) of standard deviation in respects to the average value of the distances between the adjacent intersection points of the straight line and the conductive heating line is 5% or more, the pattern is formed of the closed figures having continuous distribution, and the ratio (area distribution ratio) of standard

deviation in respects to the average value of the areas of the closed figures is 5% or more.

In the present invention, in the case of when the heating line pattern is formed on the transparent substance by using the following method, the line width and line height may be made uniform. According to an exemplary embodiment of the present invention, at least a portion of the conductive heating line pattern may be different from the remaining pattern. The desired heating line pattern may be obtained by this configuration. For example, in the vehicle glass, in order to ensure the view field first in the area which corresponds to the front surface of the driver, the heating line patterns of the corresponding area and the remaining area may be different from each other. The line widths and line intervals of the printing pattern may be different from each other so that at least a portion of the heating line pattern is different from the remaining printing pattern. Therefore, the heating may more rapidly or efficiently occur at a desired place.

According to an exemplary embodiment of the present invention, the heating element may include an area in which the conductive heating line is not formed. Transmission and reception that have a predetermined frequency can be performed by allowing at least a portion of the heating element not to form the conductive heating line, and information transmission and reception may be performed between the internal space and the external space. In this case, the area in which the conductive heating line is not formed may have an area that varies according to the desired frequency of the transmission and reception. For example, in order to pass the electromagnetic wave of 1.6 GHz that is used in the GPS, the area that has the long side that is 1/2 (9.4 cm) or more of the above wavelength is required. The area in which the conductive heating line is not formed may have an area that can transmit and receive the desired frequency, and its form is not particularly limited. For example, in the present invention, in order to pass the electromagnetic wave, the area in which the conductive heating line is not formed may be the heating element that is provided with one or more semicircular areas that have the diameter of 5 to 20 cm.

According to an exemplary embodiment of the present invention, the conductive heating line may be blackened. If the paste that includes the metal material is sintered at the high temperature, metal gloss is shown, such that the visibility may be lowered because of the reflection of light. The problem may be prevented by blackening the conductive heating line. In order to blacken the conductive heating line, the blackening material may be added to the paste for forming the heating line or the blackening treatment may be performed after the paste is printed and sintered, thereby blackening the conductive heating line.

As the blackening material that may be added to the paste, there are metal oxide, carbon black, carbon nanotube, black pigment, colored glass frit and the like. In this case, the composition of the paste may include 50 to 90 wt % of the conductive heating line material, 1 to 20 wt % of organic binder, 1 to 10 wt % of blackening material, 0.1 to 10 wt % of glass frit, and 1 to 20 wt % of solvent.

When the blackening treatment is performed after the sintering, the composition of the paste may include 50 to 90 wt % of the conductive heating line material, 1 to 20 wt % of organic binder, 0.1 to 10 wt % of glass frit, and 1 to 20 wt % of solvent. The blackening treatment after the sintering includes dipping into the oxidized solution, for example, solution that includes the Fe or Cu ion, dipping into the solution that includes halogen ions such as a chlorine ion, dipping into hydrogen peroxide and nitric acids, and treatment using the halogen gas.

15

In order to maximize the minimization effect of side effects by the diffraction and interference of light, the conductive heating line pattern may be formed so that the area of the pattern that is formed of the figures having the asymmetric structure is larger than the entire pattern area by 10% or more. In addition, it may be formed so that the area of the figures in which at least one of the lines that connect the central point of any one figure that forms the Voronoi diagram and the central point of the adjacent figure forming the boundary in conjunction with the figure is different from the remaining lines in views of length is larger than the entire conductive heating line pattern area by 10% or more.

When the heating line pattern is manufactured, after the pattern is designed in a limited area, the method in which the limited area is repeatedly connected is used to manufacture a large area pattern. In order to repeatedly connect the patterns, the repetitive patterns may be connected to each other by fixing the positions of the dots of each quadrilateral. In this case, the limited area has the area of preferably 1 cm² or more and more preferably 10 cm² or more in order to minimize the diffraction and interference by the repetition.

In the present invention, after the desired pattern form is determined first, the precise conductive heating line pattern that has the thin line width may be formed on the transparent substance by using a printing method, a photolithography method, a photography method, a method using a mask, a sputtering method, or an inkjet method. When the pattern form is determined, the Voronoi diagram generator may be used, such that a complex pattern form may be easily determined. Here, the Voronoi diagram generator means the dots that are disposed so that the Voronoi diagram is formed as described above. However, the scope of the present invention is not limited thereto, and the other method may be used in addition to the method for using the Voronoi diagram when the desired pattern form is determined.

The printing method may be performed by using a method in which the paste that includes the conductive heating line material is transferred on the transparent substance in the desired pattern form and sintered. The transferring method is not particularly limited, but the above pattern form is formed on the pattern transferring medium such as a intaglio or screen and the desired pattern may be transferred on the transparent substance by using this. The method for forming the pattern form on the pattern transferring medium may be performed by using the method that is known in the art.

The printing method is not particularly limited, and a printing method such as offset printing, screen printing, and gravure printing may be used. The offset printing may be performed by using the method in which after the paste is filled in the intaglio on which the pattern is formed, first transferring is performed by using silicon rubber that is called as the blanket, and the second transferring is performed by closely contacting the blanket and the transparent substance. The screen printing may be performed by using the method in which after the paste is disposed on the screen on which the pattern is formed, the paste is directly provided on the substance through the screen that has the space while the squeeze is pushed. The gravure printing may be performed by using the method in which after the paste is filled in the pattern while the blanket where the pattern is formed on the roll is wound, it is transferred on the transparent substance. In the present invention, the above method may be used and the above methods may be used in combination. In addition, the other printing method that is known to those who are skilled in the art may be used.

In the case of the offset printing method, because of the release property of the blanket, since most of the paste is

16

nearly transferred on the transparent substance such as glass, a separate blanket washing process is not required. The intaglio may be manufactured by precisely etching the glass on which the desired conductive heating line pattern is formed, and metal or DLC (diamond-like carbon) coating may be performed on the glass surface for the durability. The intaglio may be manufactured by etching the metal plate.

In the present invention, in order to implement the more precise conductive heating line pattern, it is preferable to use the offset printing method. FIG. 3 illustrates the offset printing method. According to FIG. 3, after the paste is filled in the pattern of the intaglio by using the doctor blade as the first step, the first transferring is performed by rotating the blanket, and as the second step, the second transferring is performed on the surface of the transparent substance by rotating the blanket.

In the present invention, it is not limited to the above printing method, and the photolithography process may be used. For example, the photolithography process may be performed by using the method in which the conductive heating line pattern material layer is formed on the entire surface of the transparent substance, the photoresist layer is formed thereon, the photoresist layer is patterned by the selective exposure and developing process, the conductive heating line pattern material layer is patterned by using the patterned photoresist layer as the mask, and the photoresist layer is removed.

Further, in the present invention, a manner where a metal layer is formed on an entire surface of a transparent substance, an etching resist pattern is formed by using a printing method, and a metal pattern is formed by an etching process may be used.

The present invention may use the photolithography method. For example, after the picture photosensitive material that includes silver halide is coated on the transparent substance, the pattern may be formed by selectively exposing and developing the photosensitive material. A detailed example will be described below. First, the photosensitive material for negative is coated on the substance on which the pattern will be formed. In this case, as the substance, a polymer film such as PET, acetyl cellulose and the like may be used. The polymer film material on which the photosensitive material is coated is called as the film. The photosensitive material for negative was formed of silver halide in which AgBr that was very sensitive to light and regularly reacted with it and a small amount of AgI were mixed with each other. Since the image that is developed by picturing the general photosensitive material for negative is a negative picture that is opposite to the subject in terms of light and shade, the picturing may be performed by using the mask that has the pattern form that will be formed and preferably irregular pattern form.

In order to increase the conductivity of the heating line pattern that is formed by using the photolithography and photography process, a plating treatment may be further performed. The plating may use an electroless plating method, copper or nickel may be used as the plating material, and after the copper plating is performed, nickel plating may be performed thereon, but the scope of the present invention is not limited thereto.

The present invention may use the method using the mask. For example, after the mask that has the heating pattern is disposed close to the substance, it may be patterned by using the method for depositing the heating pattern material. In this case, the depositing method may use a heat deposition method by heat or electron beam, a PVD (physi-

cal vapor deposition) method such as sputter, and a CVD (chemical vapor deposition) method using an organometal material.

In the present invention, the transparent substance is not particularly limited, but it is preferable to use the substrate where the light transmittance is 50% or more, and preferably 75% or more. In detail, glass may be used as the transparent substance, and the plastic substrate or plastic film may be used. In the case of when the plastic film is used, it is preferable that after the conductive heating line pattern is formed, glass is attached on at least one side of the substrate. In this case, it is more preferable that the glass or plastic substrate is attached to the side on which the conductive heating line pattern is formed. A material that is known in the art may be used as the plastic substrate or film, for example, it is preferable to use the film that has the visible ray transmittance of 80% or more such as PET (Polyethylene terephthalate), PVB (polyvinylbutyral), PEN (polyethylene naphthalate), PES (polyethersulfon), PC (polycarbonate), and acetyl cellulose. The thickness of the plastic film is preferably 12.5 to 500 micrometers, and more preferably 50 to 250 micrometers.

In the present invention, it is preferable that as the conductive heating material, metal that has an excellent thermal conductivity is used. In addition, the specific resistance value of the conductive heating line material is in the range of 1 microOhm cm to 200 microOhm cm. As a detailed example of the conductive heating line material, copper, silver, carbon nanotube (CNT) may be used, and silver is most preferable. The conductive heating line material may be used in a particle form. In the present invention, as the conductive heating line material, copper particles that are coated with silver may be used.

In the present invention, in the case of when the paste that includes the conductive heating line material is used, the paste may further include an organic binder in addition to the conductive heating line material so as to easily perform the printing process. It is preferable that the organic binder has a volatile property in the sintering process. As the organic binder, there are polyacryl resin, polyurethane resin, polyester resin, polyolefine resin, polycarbonate resin and cellulose resin, polyimide resin, polyethylene naphthalate resin and denatured epoxy resin, but it is not limited thereto.

In order to improve the attachment ability of the paste to the transparent substance such as glass, the paste may further include a glass frit. The glass frit may be selected from commercial products, but it is preferable to use the environmentally friendly glass frit that includes no lead component. In this case, it is preferable that the average diameter of the glass frit is 2 micrometers or less and the maximum diameter thereof is 50 micrometers or less.

If necessary, a solvent may be further added to the paste. As the solvent, there are butyl carbitol acetate, carbitol acetate, cyclohexanon, cellosolve acetate) and terpineol, but it is not limited thereto.

In the present invention, in the case of when the paste that includes the conductive heating line material, organic binder, glass frit and solvent is used, it is preferable that the weight ratio of the conductive heating line material is 50 to 90%, the weight ratio of the organic binder is 1 to 20%, the weight ratio of the glass frit is 0.1 to 10% and the weight ratio of the solvent is 1 to 20%.

It may be formed so that the line width of the conductive heating line is 100 micrometers or less, preferably 30 micrometers or less, more preferably 25 micrometers or less.

In the present invention, in the case of when the above paste is used, if the paste is sintered after it is printed in the

above pattern, the heating line pattern that has the conductivity is formed. In this case, the sintering temperature is not particularly limited, but it may be 500 to 800° C. and preferably 600 to 700° C. In the case of when the transparent substance that forms the heating line pattern is glass, if necessary, in the above sintering step, the glass may be shaped for the purpose of construction or vehicles. For example, in the step for shaping the glass for vehicles in a curved line, the paste may be sintered. In addition, in the case of when the plastic substrate or film is used as the transparent substance that forms the conductive heating pattern, it is preferable that the sintering is performed at a relatively low temperature. For example, it may be performed at 50 to 350° C.

In the method for manufacturing the heating element according to an exemplary embodiment of the present invention, the step for forming the bus bar that is electrically connected to the conductive heating line and the step for providing the power portion that is connected to the bus bar are performed. These steps may use a method that is known in the art. For example, the bus bar may be simultaneously formed in conjunction with the formation of the conductive heating line, and may be formed by using the same or other printing method after the conductive heating pattern is formed. For example, after the conductive heating line is formed by using the offset printing method, the bus bar may be formed through the screen printing. In this case, it is appropriate that the thickness of the bus bar is 1 to 100 micrometers and it is preferably 10 to 50 micrometers. If it is less than 1 micrometer, since the contact resistance between the conductive heating line and the bus bar is increased, local heating may be performed at the contact portion, and if it is more than 100 micrometers, the cost of the electrode material is increased. The connection between the bus bar and power may be performed through soldering and physical contact to the structure that has good conductive heating.

In order to conceal the conductive heating line and the bus bar, the black pattern may be formed. The black pattern may be printed by using the paste that includes cobalt oxides. In this case, it is appropriate the printing method is the screen printing, and its thickness is 10 to 100 micrometers. The conductive heating line and the bus bar may be formed before or after the black pattern is formed.

The heating element according to an exemplary embodiment of the present invention includes an additional transparent substance that is provided on a side on which the conductive heating line of the transparent substance is provided. When the additional transparent substance is attached, an adhesive film may be provided between the conductive heating line and additional transparent substance. In the course of attaching them, the temperature and pressure may be controlled.

In one detailed embodiment, the attachment film is inserted between the transparent substance on which the conductive heating pattern is formed and additional transparent substance, and they are put into the vacuum bag, and reduced in pressure or increased in temperature or increased in temperature by using the hot roll, thus removing the air, thereby accomplishing the first attachment. In this case, the pressure, temperature and time may vary according to the kind of the attachment film, and in general, the temperature may be gradually increased from normal temperature to 100° C. at a pressure of 300 to 700 Torr. In this case, it is preferable that the time is generally 1 hour or less. The preliminarily attached layered structure that is first attached is subjected to the second attachment process by the auto-

clave process where the temperature is increased while the pressure is added in the autoclave. The second attachment varies according to the kind of the attachment film, but it is preferable that after the attachment is performed at the pressure of 140 bar or more and the temperature in the range of 130 to 150° C. for 1 to 3 hours, and preferably about 2 hours, it is slowly cooled.

In the other detailed embodiment, the method for attaching them through one step by using the vacuum laminator device unlike the above two step attachment process may be used. The attachment may be performed by stepwisely increasing the temperature to 80 to 150° C. and cooling them so that the pressure is lowered (~5 mbar) until the temperature is 100° C. and thereafter the pressure is added (~1000 mbar).

Here, any material that has an adhesive strength and is transparent after attaching may be used as the material of the adhesive film. For example, the PVB film, EVA film, PU film and the like may be used, but is not limited thereto. The adhesive film is not particularly limited, but it is preferable that its thickness is in the range of 100 micrometers to 800 micrometers.

In the above method, the additional attached transparent substance may be formed of only the transparent substance and may be formed of the transparent substance that is provided with the conductive heating line that is manufactured as described above.

It is preferable that the line width of the conductive heating line of the heating element is 100 micrometers or less, preferably 30 micrometers or less, more preferably 10 micrometers or less and 2 micrometers or more. The interval between the lines of the conductive heating line is preferably 30 mm or less, preferably 50 micrometers to 10 mm, and preferably 200 micrometers to 0.1 mm. The height of the heating line is 1 to 100 micrometers, and more preferably 1 to 3 micrometers. The line width and line height of the heating line may be made uniform by the above methods. In the present invention, the uniformity of the heating line may be in the range of ± 3 micrometers in the case of the line width and in the range of ± 1 micrometer in the case of the line height.

The heating element according to an exemplary embodiment of the present invention may to the power for heating, and in this case, the heating amount is 100 to 700 W per m^2 , and preferably 200 to 300 W. Since the heating element according to an exemplary embodiment of the present invention has excellent heating performance at the low voltage, for example, 30 V or less, and preferably 20 V or less, it may be usefully used in vehicles and the like. The resistance of the heating element is 5 ohm/square or less, preferably 1 ohm/square or less, and more preferably 0.5 ohm/square or less.

The heating element according to an exemplary embodiment of the present invention may have a shape of curved surface.

In the heating element according to an exemplary embodiment of the present invention, it is preferable that the opening ratio of the conductive heating line pattern, that is, the area ratio of the glass that is not covered with the pattern is 70% or more. The heating element according to an exemplary embodiment of the present invention has an excellent heating property where an opening ratio is 70% or more, the temperature deviation within 5 min after heating operation is maintained at 10%, and the temperature is increased.

The heating element according to an exemplary embodiment of the present invention may be applied to glass that is

used for various transport means such as vehicles, ships, railroads, high-speed railroads, and airplanes, houses or other buildings. In particular, since the heating element according to an exemplary embodiment of the present invention has an excellent heating property at a low voltage, can minimize side effects by diffraction and interference of light source after sunset, and can be invisible in the above line width, unlike the known technology, it may be applied to the front window for transport means such as vehicles.

10

MODE FOR INVENTION

Hereinafter, the present invention is illustrated through Examples, but the scope of the present invention is not limited by them.

15

Example 1

The silver paste was manufactured by dissolving 80 wt % of silver particles that had the particle diameter of 2 micrometers, 5 wt % of polyester resin, 5 wt % of glass frit in 10 wt % of BCA (butyl carbitol acetate) solvent. As the intaglio, the glass that had the width of 20 micrometers, the depth of 7.5 micrometers, and the average interval between lines of 600 micrometers and the same pattern as FIG. 1 was used. In this case, when the straight line that intersected the formed pattern was drawn, the ratio (distance distribution ratio) of standard deviation in respects to an average value of distances between adjacent intersection points of the straight line and the electric conductive pattern was about 30%.

20

After the silver pattern was formed on the glass substrate (100 mm $\times$ 100 mm) by using the method that was shown in FIG. 3 and the offset printer, it was sintered at 600° C. for about 3 min to form the heating line shown in FIG. 1.

25

The surface resistance of the glass substrate that had the heating line was 1.2 ohm/square, and the bus bar was formed by contacting the copper strip on the pattern by the clip in the direction of 100 mm. In this case, the resistance between both terminals was 1.5 ohm. In this case, when the voltage of 2.8 V was applied, the heating amount was 5.1 W (510 W/ m^2). As a result of the measurement of the heating phenomenon by using the IR vision camera, the temperature was increased from 20° C. to 40° C. within 20 min. In addition, the temperature deviation percentage value that was obtained by dividing the difference between the maximum value and the minimum value of the temperatures that were measured 20 points by the average value was 6% or less for the measurement time. The visible ray transmittance of the glass that had the heating line was 80% or more.

30

When the equipment shown in KS L 2007 was used, the incandescent lamp of 100 W (general bulb having a predetermined brightness was used) was installed at the distance of 7 m from the glass substrate that had the heating line, and light that is emitted from the light source penetrates the glass substrate that had the heating line, the digital image of 1600 $\times$ 1200 pixels was obtained by using. On the basis of the center of the light source, the image had the pixels within the distance of 500, the average value of the intensity of light per each 5°, and standard deviation value of the average values was calculated. The standard deviation value was 12.1. In addition, predetermined patterns by scattering of light were not observed around the light source.

35

Example 2

40

The silver paste was manufactured by dissolving 80 wt % of silver particles that had the particle diameter of 2 microm-

21

eters, 5 wt % of polyester resin, 5 wt % of glass frit in 10 wt % of BCA (butyl carbital acetate) solvent. As the intaglio, the glass that had the width of 20 micrometers, the depth of 7.5 micrometers and the same pattern as FIG. 5 was used.

After the silver pattern was formed on the glass substrate (100 mm×100 mm) by using the method that was shown in FIG. 2 and the offset printer, it was sintered at 600° C. for about 3 min to form the heating line shown in FIG. 5. In this case, when the straight line that intersected the formed pattern was drawn, the ratio (distance distribution ratio) of standard deviation in respects to an average value of distances between adjacent intersection points of the straight line and the electric conductive pattern was about 50%.

In this case, the surface resistance was 1.0 ohm/square, and resistance between both ends of the glass substrate of 100 mm×100 mm was 1.0 ohm. The visible ray transmittance of the glass that had the conductive heating line pattern was 70%.

The light intensity experiment was performed by using the same method as Example 1. In this case, the standard deviation value of the intensity of light for each angle was 5. In addition, predetermined patterns by scattering of light were observed around the light source.

Comparative Example 1

The grid pattern on the basis of the square of 0.09 mm² was manufactured, and the figure of the pattern was the same as that of FIG. 6. In this case, when the straight line that intersected the formed pattern was drawn, the ratio (distance distribution ratio) of standard deviation in respects to an average value of distances between adjacent intersection points of the straight line and the electric conductive pattern was about 0%. In this case, the surface resistance was 0.4 ohm/square, and resistance between both ends of the glass substrate of 100 mm×100 mm was 0.4 ohm. The visible ray transmittance of the patterned glass was 74%. The light intensity experiment was performed by using the same method as Example 1. In this case, the standard deviation value of the intensity of light for each angle was 19.5. In addition, the strong interference patterns that had the cross shape were observed around the light source.

Comparative Example 2

The same pattern as that of FIG. 7 was manufactured (pitch 0.3 mm). In this case, when the straight line that intersected the formed pattern was drawn, the ratio (distance distribution ratio) of standard deviation in respects to an average value of distances between adjacent intersection points of the straight line and the electric conductive pattern was about 0%. In this case, the surface resistance was 0.8 ohm/square, and resistance between both ends of the glass substrate of 100 mm×100 mm was 0.79 ohm. The visible ray transmittance of the patterned glass was 70%.

Example 3

The photosensitive material for negative was coated on the PET film substrate on which the pattern will be formed. The photosensitive material for negative was formed of silver halide in which AgBr that was very sensitive to light and regularly reacted with it and a small amount of AgI were mixed with each other. The irregular pattern that was formed on the PET film substrate was the same as the pattern of Example 1. By using the negative mask that was configured that light was penetrated through the designed pattern area

22

and light was not penetrated through a portion that did not correspond to the pattern, light was irradiated to the film according to the set exposure time and intensity of light. By this process, photosensitive silver on the photosensitive emulsion layer was photosensitized to form a latent image. The inversion pattern of the mask pattern was formed in a visible phase by converting photosensitive silver into blackened silver through the development process of the formed latent image. The properties of the pattern that was made of blackened silver formed on the PET film substrate through the photograph process.

TABLE 3

Line width (micrometer)	Line height (micrometer)	Transmittance (%)
20	6.5	75.6

The film was laminated on the glass by using the adhesive film. In this case, the surface resistance was 0.1 ohm/square, and resistance between both ends of the glass substrate of 100 mm×100 mm was 0.2 ohm. The light intensity experiment was performed by using the same method as Example 1. In this case, the standard deviation value of the intensity of light for each angle was 12.1. In addition, predetermined patterns by scattering of light were not observed around the light source.

Examples 4 to 19 and Comparative Example 3

After the copper thin film having the thickness of 2 micrometers was formed on the PET substrate, the etching resist pattern was formed by using the printing process, and the pattern as illustrated in FIG. 22 was formed through the etching process. In order to form the pattern, as illustrated in FIG. 20(A), the regular hexagon honeycomb structure started as the basic unit, and the unit area by which the position of the vertex of the hexagon is changed was designated as FIG. 20(A) and the circle. The randomness was adjusted by the ratio of the diameter of the circle that was the unit area and the length of one side of the basic unit. That is, the randomness may be defined as the value obtained by dividing the diameter of the circle that was the unit area by the length of the side of the basic unit. In this case, if the value of the randomness is 0%, the regular honeycomb structure is attained, and as the randomness is increased, the randomness of the pattern is increased. In the aforementioned unit area, each vertex was randomly selected, and in this case, the value of the randomness is described in the following Table 1.

For the manner of linking the vertexes where the positions were changed according to the randomness with each other, the curved line was selected. As illustrated in FIG. 20(C), when regardless of the length between the vertexes, when the straight lines are drawn from the original point of the circle to the two vertexes of the polygon, the curved line was formed by the manner so that the angle θ_c formed by the two straight lines was constant, and in this case, the used angle is described in the following Table 1.

Ten or more predetermined straight lines were drawn in the pattern formed as illustrated in FIG. 22, the lengths between intersection points with the pattern were measured to obtain the average and the standard deviation, and the smallest value among the values obtained by dividing the standard deviation by the average was selected, and is described in Table 1.

By using the equipment illustrated in FIG. 8, the standard deviation value of the intensity of light for each 5° in the circumferential direction of the light source which is measured when light that is emitted from the light source that is disposed at the distance of 7 m from the heating element measured by the aforementioned manner passes through the heating element was measured, and is described in Table 1.

TABLE 1

	Randomness (%)	Curvature ($^\circ$)	Standard deviation/Average distance (%)	Standard deviation according to light dispersion
Comparative Example 3	0	0	0	19.5
Example 4	20	20	5.61	7.84
Example 5		40	8.41	6.26
Example 6		60	7.87	2.87
Example 7		80	7.16	1.67
Example 8	40	20	11.59	3.97
Example 9		40	11.75	3.39
Example 10		60	10.15	2.05
Example 11		80	15.08	1.49
Example 12	60	20	27.04	1.98
Example 13		40	31.62	1.44
Example 14		60	25.52	1.21
Example 15		80	41.31	1.13
Example 16	80	20	39.05	1.35
Example 17		40	37.01	0.96
Example 18		60	36.01	0.63
Example 19		80	49.12	0.46

The value obtained by dividing the standard deviation in respects to the distance illustrated in Table 1 by the average distance, and the standard deviation according to light scattering are illustrated in the following FIG. 27. When the value obtained by dividing the standard deviation in respects to the distance by the average distance was 0%, the strong interference pattern illustrated in the Comparative Example of FIG. 9 was largely weakened when the value obtained by dividing the standard deviation in respects to the distance by the average distance was 5% or more. Accordingly, it can be seen that the standard deviation value according to light scattering has the value of a half or less. Particularly, it could be confirmed that when the value was 10% or more, the standard deviation value according to light scattering had the value of 5 or less, and thus the interference pattern according to light scattering was weakened.

Example 20

The silver paste was manufactured by dissolving 80 wt % of silver particles that had the particle diameter of 2 micrometers, 5 wt % of polyester resin, 5 wt % of grass frit in 10 wt % of BCA (butyl carbitol acetate) solvent. As the intaglio, the glass that had the width of 20 micrometers, the depth of 7.5 micrometers and the Voronoi pattern was used. The Voronoi pattern that was the same as that of FIG. 10 was manufactured by setting the square of 0.09 mm^2 as the basic unit and providing irregularity to the distribution of dots in the basic unit. The ratio of the area distribution of the closed figure of the pattern was 23%.

After the silver pattern was formed on the glass substrate (100 mm $\times$ 100 mm) by using the method that was shown in FIG. 3 and the offset printer, it was sintered at 600°C. for about 3 min to form the pattern shown in FIG. 10. The surface resistance of the glass substrate was 0.6 ohm/square, and the bus bar was formed by contacting the copper strip on

the pattern by the clip in the direction of 100 mm. In this case, the resistance between both terminals was 0.6 ohm. In this case, when the voltage of 1.8 V was applied, the heating amount was 5.4 W (540 W/m^2). As a result of the measurement of the heating phenomenon by using the IR vision camera, the temperature was increased from 20°C. to 40°C. within 20 min. In addition, the temperature deviation percentage value that was obtained by dividing the difference between the maximum value and the minimum value of the temperatures that were measured 20 points by the average value was 6% or less for the measurement time. The visible ray transmittance of the glass that had the conductive heating line pattern was 80%.

When the equipment shown in KS L 2007 was used, the incandescent lamp of 100 W (general bulb having a predetermined brightness was used) was installed at the distance of 7 m from the glass substrate that had the heating line, and light that is emitted from the light source penetrates the glass substrate that had the heating line, the digital image of 15 1600 $\times$ 1200 pixels was obtained by using. On the basis of the center of the light source, the image had the pixels within the distance of 500, the average value of the intensity of light per each 5° , and standard deviation value of the average values was calculated. The standard deviation value was 2. In 20 25 addition, predetermined patterns by scattering of light were not observed around the light source.

Example 21

30 The silver paste was manufactured by dissolving 80 wt % of silver particles that had the particle diameter of 2 micrometers, 5 wt % of polyester resin, 5 wt % of grass frit in 10 wt % of BCA (butyl carbitol acetate) solvent. As the intaglio, the glass that had the width of 20 micrometers, the depth of 35 10 micrometers and the Delaunay pattern was used. The Delaunay pattern as shown in FIG. 15 was manufactured after being formed by making the distribution of dots in the basic unit of 0.09 mm^2 irregular. The ratio of the area distribution of the closed figure of the pattern was 20%.

40 After the silver pattern was formed on the glass substrate (100 mm $\times$ 100 mm) by using the method that was shown in FIG. 3 and the offset printer, it was sintered at 600°C. for about 3 min to form the pattern shown in FIG. 15. The surface resistance of the glass substrate was 1.0 ohm/square, 45 and the bus bar was formed by contacting the copper strip on the pattern by the clip in the direction of 100 mm. In this case, the resistance between both terminals was 0.8 ohm. In this case, when the voltage of 2.0 V was applied, the heating amount was 5.0 W (500 W/m^2). As a result of the measurement of the heating phenomenon by using the IR vision camera, the temperature was increased from 20°C. to 40°C. within 20 min. In addition, the temperature deviation percentage value that was obtained by dividing the difference between the maximum value and the minimum value of the temperatures that were measured 20 points by the average value was 6% or less for the measurement time. The visible ray transmittance of the glass that had the conductive heating line pattern was 70%. In this case, the standard deviation value of the intensity of light for each angle was 55 60 1.5.

In addition, predetermined patterns by scattering of light were not observed around the light source.

Example 22

The same method as Example 20 was performed, except that only the basic unit was changed into 0.25 mm^2 . In this

case, the used pattern was the same as FIG. 16. The ratio of the area distribution of the closed figure of the pattern was 20%. In this case, the surface resistance was 1.2 ohm/square, and resistance between both ends of the glass substrate of 100 mm×100 mm was 1.5 ohm. The visible ray transmittance of the glass that had the conductive heating line pattern was 83%. In this case, the standard deviation value of the intensity of light for each angle was 1.4. In addition, predetermined patterns by scattering of light were not observed around the light source.

Example 23

The same method as Example 21 was performed, except that only the basic unit was changed into 0.25 mm². In this case, the used pattern was the same as FIG. 17. The ratio of the area distribution of the closed figure of the pattern was 20%. In this case, the surface resistance was 1.2 ohm/square, and resistance between both ends of the glass substrate of 100 mm×100 mm was 1.0 ohm. The visible ray transmittance of the glass that had the conductive heating line pattern was 76%. In this case, the standard deviation value of the intensity of light for each angle was 2.0. In addition, predetermined patterns by scattering of light were not observed around the light source.

Comparative Example 4

The grid pattern on the basis of the square of 0.09 mm² was manufactured, and the figure of the pattern was the same as that of FIG. 6. The ratio of the area distribution of the closed figure of the pattern was 0%. In this case, the surface resistance was 0.4 ohm/square, and resistance between both ends of the glass substrate of 100 mm×100 mm was 0.4 ohm. The visible ray transmittance of the glass that had the conductive heating line pattern was 74%.

The light intensity experiment was performed by using the same method as Example 20. In this case, the standard deviation value of the intensity of light for each angle was 19.5. In addition, the strong interference patterns that had the cross shape were observed around the light source.

In the case of when the pattern of FIG. 6 shown as Comparative Example was used, the strong interference patterns that had the cross shape were observed around the light source. However, in the case of Examples, the scattering by the pattern was observed, but predetermined patterns were not observed.

Examples 24 to 39 and Comparative Example 5

The area distributions of the closed figures were analyzed by using the patterns of Examples 4 to 19, and are described in the following Table 2. In this case, in order to calculate the area distribution of the closed figure, 200 or more closed figures were randomly selected, and the average and the standard deviation thereof were calculated.

TABLE 2

	Randomness (%)	Curvature (°)	Standard deviation/ Average area (%)	Standard deviation according to light dispersion
Comparative Example 5	0	0	0	19.5
Example 24	20	20	6.5	7.84
Example 25		40	7.6	6.26

Example 39		80	29.3	0.46

The value obtained by dividing the standard deviation in respects to the area of the closed figure illustrated in Table 2 by the average area, and the standard deviation according to light scattering are illustrated in the following FIG. 24. When the value obtained by dividing the standard deviation in respects to the area of the closed figure by the average area was 0%, the strong interference pattern illustrated in the Comparative Example of FIG. 9 was largely weakened when the value obtained by dividing the standard deviation in respects to the area of the closed figure by the average area was 5% or more, and thus it can be seen that the standard deviation value according to light scattering has the value of a half or less. Particularly, it could be confirmed that when the value was 10% or more, the standard deviation value according to light scattering had the value of 5 or less, and thus the interference pattern according to light scattering was weakened.

Further, in Examples 24 to 39, the forms where the randomness and curvature of the pattern are modified are more specifically illustrated in the following FIG. 22.

As described above, the heating element according to the present invention may minimize side effects by diffraction and interference of the light source after sunset, may have excellent heat emitting performance at a low voltage, and may be manufactured as the heating element that is not visible. Further, since the heating element according to the present invention may be formed by using various methods such as a printing method, a photolithography method, a photography method, a method using a mask, a sputtering method, or an inkjet method after a target pattern is previously set, the process is easily performed and the cost thereof is low.

Examples 40 to 44 and Comparative Example 6

After the copper thin film having the thickness of 2 micrometers was formed on the PET substrate, the etching resist pattern was formed by using the printing process, and the pattern as illustrated in FIG. 23 was formed through etching. In order to form the pattern, the grid pattern was obtained by configuring the quadrangle as the basic unit and using the Voronoi pattern generator for the center point of mass of the quadrangle. In this case, the randomness of the formed pattern was defined as 0%. The randomness may be adjusted by forming the quadrangle at the percentage of the length of the side of the basic unit based on the center point of mass and then randomly changing the position of the Voronoi generator therein. Accordingly, the formed pattern is illustrated in FIG. 23.

In the pattern formed as illustrated in FIG. 23, in order to calculate the area distribution of the closed figure, 200 or more closed figures were randomly selected, and the average and the standard deviation thereof were calculated.

By using the equipment illustrated in FIG. 8, the standard deviation value of the intensity of light for each 5° in the circumferential direction of the light source which is measured when light that is emitted from the light source that is disposed at the distance of 7 m from the heating element manufactured by the aforementioned manner passes through the heating element was measured, and is described in the following Table 3.

TABLE 3

	Randomness (%)	Standard deviation/Average area (%)	Standard deviation according to light dispersion
Comparative Example 6	0	0	19.5
Example 40	10	2.83	11.2
Example 41	30	7.98	4.92
Example 42	50	12.68	4.53
Example 43	70	17.45	3.13
Example 44	100	25.33	2.00

The value obtained by dividing the standard deviation in respects to the area of the closed figure illustrated in Table 3 by the average area, and the standard deviation according to light scattering are illustrated in the following FIG. 30. When the value obtained by dividing the standard deviation in respects to the area of the closed figure by the average area was 5% or less, the strong interference pattern illustrated in the Comparative Example of FIG. 9 was largely weakened when the value obtained by dividing the standard deviation in respects to the area of the closed figure by the average area was 5% or more, and thus it can be seen that the standard deviation value according to light scattering has the value of a half or less. Particularly, it could be confirmed that when the value was 10% or more, the standard deviation value according to light scattering had the value of 5 or less, and thus the interference pattern according to light scattering was weakened.

The invention claimed is:

1. A heating element comprising:
a transparent substance;
a conductive heating line that is provided on at least one side of the transparent substance; and
a bus bars that is electrically connected to the conductive heating line,
wherein 30% or more of the entire area of the transparent substance has a conductive heating line pattern in which, when a straight line that intersects the conductive heating line is drawn, a ratio of a standard deviation of distances between adjacent intersection points of the straight line and the conductive heating line to an average value of distances between adjacent intersection points of the straight line and the conductive heating line is 5% or more, and
wherein the conductive heating line pattern comprises shapes with linked vertexes after a basic unit of a regular polygon is designated and positions of each vertex of the polygon is randomly changed within a unit area that has a circular shape with the vertex of the polygon as its center and a length of any one side of the polygon as its diameter.

2. The heating element according to claim 1, wherein the straight line that intersects the conductive heating line is a line in which the standard deviation of the distances between adjacent intersection points of the straight line and the conductive heating line is the smallest value.

3. The heating element according to claim 1, wherein the straight line that intersects the conductive heating line is a straight line that vertically extends in respects to a tangent line of any one point of the conductive heating line.

4. The heating element according to claim 1, wherein the straight line that intersects the conductive heating line has 80 or more intersection points of the straight line and the conductive heating line.

5. The heating element according to claim 1, wherein the ratio of a standard deviation of distances between adjacent intersection points of the straight line and the conductive heating line to an average value of distances between adjacent intersection points of the straight line and the conductive heating line is 20% or more.

6. The heating element according to claim 1, wherein the conductive heating line has a boundary pattern of figure that form a Voronoi diagram.

7. The heating element according to claim 1, wherein in the conductive heating line, a line width is from 2 micrometers to 100 micrometers, an interval between lines is from 50 micrometers to 30 mm, and a height of the line from the surface of the transparent substance is in the range of 1 to 100 micrometers.

8. The heating element according to claim 1, wherein another transparent substance is further provided on a side on which the conductive heating line of the transparent substance is provided.

9. The heating element according to claim 1, wherein a transmittance deviation of a predetermined circle that has a diameter of 20 cm is 5% or less.

10. The heating element according to claim 1, wherein the transparent substance is glass, plastic substrate or plastic film.

11. The heating element according to claim 1, wherein in the heating element, an opening ratio is 70% or more, a surface resistance is 5 ohm/square or less, and a heating amount is 100 to 500 W per m².

12. The heating element as set forth in claim 1, wherein the heating element includes at least two areas that have different patterns that are configured by the conductive heating line.

13. The heating element as set forth in claim 1, wherein the heating element includes an area in which the conductive heating line is not formed.

14. The heating element as set forth in claim 1, wherein the conductive heating line is blackened.

15. The heating element as set forth in claim 1, wherein the heating element is for a front window of a vehicle.

16. The heating element as set forth in claim 1, wherein the standard deviation value of the intensity of light for each 5° in a circumferential direction of the light source which is measured when the light emitted from the light source that is disposed at the distance of 7 m from the heating element passes through the heating element is 15 or less.

17. The heating element as set forth in claim 1, wherein the polygon is a triangle, a rectangle, a square, a direct hexagon, or a regular hexagon.

18. A method for manufacturing a heating element, the method comprising:
forming a conductive heating line on a transparent substance; and

29

forming a bus bars that is electrically connected to the conductive heating line,
 wherein, on 30% or more of the entire area of the transparent substance, the heating line is formed in a pattern in which, when a straight line that intersects the conductive heating line pattern is drawn, a ratio of a standard deviation of distances between adjacent intersection points of the straight line and the conductive heating line pattern to an average value of distances between adjacent intersection points of the straight line and the conductive heating line is 5% or more,
 wherein the conductive heating line pattern comprises shapes with linked vertexes after a basic unit of a regular polygon is designated and positions of each vertex of the polygon is randomly changed within a unit area that has a circular shape with the vertex of the polygon as its center and a length of any one side of the polygon as its diameter.

19. The method for manufacturing a heating element according to claim 18, wherein the conductive heating line is formed by using a printing method, a photolithography method, a photography method, a method using a mask, a sputtering method, or an inkjet method.

20. The method for manufacturing a heating element according to claim 18, wherein in the conductive heating line, a line width is from 2 micrometers to 100 micrometers, an interval between lines is from 50 micrometers to 30 mm, and a height of the line from the surface of the transparent substance is in the range of 1 to 100 micrometers.

21. A heating element comprising:

a transparent substance;
 a conductive heating line that is provided on at least one side of the transparent substance; and
 a bus bars that is electrically connected to the conductive heating line,
 wherein 30% or more of the entire area of the transparent substance has a conductive heating line pattern that is formed of closed figures,

wherein a distribution is continuous and a ratio of a standard deviation of areas of the closed figures to an average value of the areas of the closed figures is 5% or more,

wherein the conductive heating line pattern comprises polygonal shapes with linked vertexes after a basic unit of a regular polygon is designated and positions of each vertex of the polygon is randomly changed within a unit area that has a circular shape with the vertex of the polygon as its center and a length of any one side of the polygon as its diameter, or

wherein the conductive heating line pattern comprises polygonal shapes modified so that changed center points of mass become new center points of mass after a basic unit of a regular polygon is designated and positions of the center points of mass of the polygon are randomly changed in the polygon.

22. The heating element according to claim 21, wherein 30% or more of the entire area of the transparent substance has a conductive heating line pattern that is formed of closed figures wherein a distribution is continuous and a ratio of a standard deviation of areas of the closed figures to an average value of the areas of the closed figures is 20% or more.

23. The heating element according to claim 21, wherein there are at least 100 closed figures.

24. The heating element according to claim 21, wherein the conductive heating line has a boundary pattern of figures that form a Voronoi diagram.

30

25. The heating element according to claim 21, wherein the conductive heating line has a boundary pattern of figures that are formed of at least one triangle that forms a Delaunay pattern.

26. The heating element according to claim 21, wherein in the conductive heating line, a line width is from 2 micrometers to 100 micrometers, an interval between lines is from 50 micrometers to 30 mm, and a height of the line from the surface of the transparent substance is in the range of 1 to 100 micrometers.

27. The heating element according to claim 21, wherein another transparent substance is further provided on a side on which the conductive heating line of the transparent substance is provided.

28. The heating element according to claim 21, wherein a transmittance deviation of a predetermined circle that has a diameter of 20 cm is 5% or less.

29. The heating element according to claim 21, wherein the transparent substance is glass, plastic substrate or plastic film.

30. The heating element according to claim 21, wherein in the heating element, the opening ratio is 70% or more.

31. The heating element according to claim 21, wherein in the heating element, a surface resistance is 5 ohm/square or less, and a heating amount is 100 to 500 W per m².

32. The heating element according to claim 21, wherein the heating element includes at least two areas that have different patterns that are configured by the conductive heating line.

33. The heating element according to claim 21, wherein the heating element includes an area in which the conductive heating line is not formed.

34. The heating element according to claim 21, wherein the conductive heating line is blackened.

35. The heating element according to claim 21, wherein the heating element is for a front window of a vehicle.

36. The heating element according to claim 21, wherein the standard deviation value of the intensity of light for each 5° in a circumferential direction of the light source which is measured when the light that is emitted from the light source that is disposed at the distance of 7 m from the heating element passes through the heating element is 15 or less.

37. The heating element as set forth in claim 21, wherein the polygon is a triangle, a rectangle, a square, a direct hexagon, or a regular hexagon.

38. A method for manufacturing a heating element, the method comprising:

forming a conductive heating line pattern on a transparent substance; and

forming a bus bars that is electrically connected to the conductive heating line pattern,

wherein, on 30% or more of the entire area of the transparent substance, the conductive heating line pattern is formed in which, when a straight line that crosses the conductive heating line is drawn, a ratio of standard deviation of the distances between adjacent intersection points of the straight line to an average value of distances between adjacent intersection points of the straight line and the conductive heating line pattern is 5% or more,

wherein the conductive heating line pattern comprises polygonal shapes with linked vertexes after a basic unit of a regular polygon is designated and positions of each vertex of the polygon is randomly changed within a unit area that has a circular shape with the vertex of the polygon as its center and a length of any one side of the polygon as its diameter, or

wherein the conductive heating line pattern comprises polygonal shapes modified so that changed center points of mass become new center points of mass after a basic unit of a regular polygon is designated and positions of the center points of mass of the polygon are 5 randomly changed in the polygon.

39. The method for manufacturing a heating element according to claim **38**, wherein the conductive heating line pattern is formed by using a printing method, a photolithography method, a photography method, a method using a 10 mask, a sputtering method, or an inkjet method.

40. The method for manufacturing a heating element according to claim **38**, further comprising before the conductive heating line pattern is formed on the transparent substance, determining the conductive heating line pattern 15 by using a Voronoi diagram generator or a Delaunay pattern generator.

41. The method for manufacturing a heating element according to claim **38**, wherein in the conductive heating line pattern, a line width is from 2 micrometers to 100 20 micrometers, an interval between lines is from 50 micrometers to 30 mm, and a height of the line from the surface of the transparent substance is in the range of 1 to 100 micrometers.
